EARTH BORING TOOL

Arthur F. Spengler, Oklahoma City, Okla.

Application December 9, 1930, Serial No. 501,010
Renewed June 5, 1934

3 Claims. (Cl. 255—71)

My invention relates to earth boring tools and has particular reference to a rock bit and reamer assembly for drilling holes such as for oil wells.

In drilling a bore into the earth the penetration of the various strata of the earth met in the course of the bore requires the employment of a hard surfaced bit for making the initial penetration which should be followed by a reamer which reams out the hole made by the bit to the proper 10 desired diameter. The boring operation requires the transmission of a flushing fluid to the faces of the bit to wash the detritus out of the bore and to clean the bit. Also a lubricating fluid is required to be supplied to the bit to assist in boring 15 through particularly hard or abrasive strata.

To provide a tool which is sufficiently rigid to properly support a bit and to transmit the power required to rotate the bit during the drilling operation requires a relatively heavy construction 20 of the bit carrier while at the same time the passages which are required to allow the lubricating and flushing fluids to pass limits the size of the construction of the bit carrier.

It is an object of my invention to provide a 25 bit carrier assembly which will provide ample space for the passage of flushing and lubricating fluids and for the location of reamers in the sides of the bit carrier without sacrificing the rigidity of the carrier which is required for transmitting 30 power to the bit.

Another object of my invention is to provide a 35 reamer and rock bit assembly in which a plurality of reamers are set into pockets formed in the sides of the bit carrier and which is provided with an interior opening through which flushing and lubricating fluids may pass.

Another object of my invention is to provide a 40 rock bit and reamer assembly in which a plurality of rotatable reamers are set into pockets formed in the walls of the reamer carrier and through the interior of which carrier conduits for flushing and lubricating fluids may be passed to connect directly with the rock bit secured to the 45 carrier.

Another object of my invention is to provide a 50 rock bit assembly of the cone type in which the cone carrier is divided longitudinally into two complementary sections, each of which is provided with its own passages for lubricating fluids and for flushing fluids.

Another object of my invention is to provide a 55 reamer carrier assembly which may be readily assembled.

Another object of my invention is to provide a

reamer carrier assembly which is particularly adapted to a built-up construction.

My invention will be described with reference to the accompanying drawing, wherein

Figure 1 is an elevational view, partly in section, of the reamer carrier and rock bit assembly;

Figure 2 is a composite sectional view through the reamer carrier illustrating the mounting of the rotatable reamers on the reamer body, the sections illustrated being taken along the lines 10 2a—2a, 2b—2b and 2c—2c, respectively;

Figure 3 is a detail view of the construction of the shaft which mounts the rotatable reamers; and

Figure 4 is an end view of the rock bit construction which I propose to use showing the cone cutters removed.

Referring to the drawing, I have illustrated at 1 a cylindrical body member comprising an elongated cylinder having a central opening 2 extending longitudinally therethrough. The upper end of the central opening is preferably provided with an enlarged threaded portion 3 to adapt the same to securing the body member to a drill string or other power appliance, whereby 25 the body member 1 may be rotated.

Spaced around the circumference of the cylindrical body member 1 I have illustrated three reamer pockets 4, 5 and 6 which may be formed by milling slots into the side of the body member 30 1 to communicate with the central passage or opening 2. Into each of the pockets thus formed may be inserted a pair of reamer bearing blocks, 7 and 8 at the upper and lower ends of the pockets, respectively. These blocks may be retained in the body member 1 in any suitable manner, such as by welding, illustrated at 9 and 10. The upper reamer block 7 has extending longitudinally therethrough a suitable opening 11 threaded at its upper portion 12 to receive a reamer shaft 13, the upper end 14 of which may be provided with threads engaging the threaded portion 12 of the block 7. The shaft 13 preferably extends throughout substantially the entire length of the 40 reamer pocket 4 to engage an opening 15 in the lower block 8.

Referring particularly to Figure 3, it will be observed that the lower end of the shaft 13 is provided with a plurality of slots 16 extending laterally therethrough for the purpose of receiving an anchoring pin 17 to prevent rotational movement of the shaft 13 after the same has been secured in position.

It will be observed that the main body of the shaft 13 is eccentric with the ends thereof so that 55

by withdrawing the pin 17 and rotating the shaft 13 the body thereof may be moved laterally relative to the center line of the reamer proper. Thus, reamers mounted upon the body may be 5 adjusted inwardly and outwardly of the body to determine the dimensions of the reamer cut.

Surrounding the shaft 13 I have illustrated a rotatable reamer 18 of a construction familiar to those skilled in the earth boring art. In order to 10 prevent excessive wear of the bearing blocks 7 and 8 suitable hardened steel washers 19 and 20 may be interposed between the ends of the reamer 18 and the bearing blocks 8 and 7, respectively. If the washers 19 and 20 were permitted to rotate 15 they would still perform their functions as reducing wear. I prefer to prevent them from rotating by inserting through the washers suitable dowel pins 21 receivable in aligned openings in the face of the bearing blocks 7 and 8, respectively.

The inner side of the bearing pockets 4, 5 and 6 which communicates with the interior passage 2 through the body 1 should be sealed from such communication to permit the interior passage to 25 be utilized as a conduit for water or other flushing fluid which may be desired to be supplied to the bit carried by the reamer assembly. For this reason I have illustrated the inner side of each of the pockets 4, 5 and 6 as being sealed off from the 30 interior passage 2 by means of a plate 22 which may be welded or otherwise suitably secured to the associated pocket.

By referring particularly to Figure 2 it will be 35 observed that the construction thus far described provides a reamer assembly in which the cylindrical body member 1 presents an interior passage 2 therethrough which, at the point of passing the reamer pockets, is substantially triangular in configuration. It will be observed that 40 a conduit 23 for lubricating fluid may be passed through this triangular opening, of such size as to lie tangent to the plates 22; thus providing three spaces 24, 25 and 26 between the pockets for the passage of suitable flushing fluid to the rock bit.

Referring again to Figure 1, I have illustrated 45 the lower end of the body member 1 as being provided with an enlarged interior opening 27 communicating with the interior opening 2 and being provided with internal threads 28 of such configuration as to engage the threaded head 29 of a rock bit 30.

I have illustrated the rock bit 30 as being of the 50 cone cutter type in which the bit 30 is divided longitudinally along its center line 31 to form two complementary halves 32 and 32a of the bit. Each half of the bit 30 is provided with a cone cutter mounting or carrier, that associated with the half 32 being designated by the reference character 33 and that associated with bit half 32a being designated by the character 33a.

The precise construction of the cone carrier is 55 familiar to those skilled in the art of earth boring and it is not deemed necessary to be fully described herein. A lubricant passageway 34 extends upwardly from the end of the cone carrier 33 to the upper end of a stem 35 formed upon the head 29 of the bit 30. A similar lubricant passageway 34a (see Figure 4) is provided for the bit half 32a.

Each of the halves 32 and 32a of the bit 30 is 60 also provided with conduits for the passage of flushing fluid therethrough. Two of these flushing fluid passages are illustrated for each of the bit halves. The bit half 32 is illustrated as having a flushing fluid conduit 36 passing vertically

therethrough on one side of the center line of this path, while a second conduit 37 is illustrated as being provided at a corresponding position upon the opposite side of the center line of this half of the bit. It will be observed that the location of the end of the conduits 36 and 37 is such that fluid passing through either of these conduits is projected partially upon the cone which is mounted upon the carrier 33 while the remainder of the fluid is directed downwardly to the bottom of the 10 earth bore so as to clean both the cone and the bottom of the bore. By providing two of these wash pipes or flushing fluid conduits one on each side of the cone carrier, the bit and the bore are effectively cleaned both prior to entry of the cutter into the face of the bore and after it has made 15 the cut.

The conduits 36 and 37 are illustrated as comprising a bored opening 38 extending longitudinally of the bit half and terminating at the lower 20 face of the bit half with a bore of slightly reduced diameter thus permitting a pipe 39 to be inserted in the bore 38 to act as a liner for the bore. The lower end of the pipe terminates at a shoulder 40 constituting the juncture of the 25 smaller bore with the larger.

The pipe 39 may be secured in the bore in any suitable manner, though I prefer to thread this pipe into the bore as by providing suitable threads 41 near the upper end of the bore to engage corresponding threads upon the pipe 39. The upper end of the pipe 42 is preferably formed square or hexagonal to permit engagement thereof by a suitable wrench required to tighten the pipe in the bore in assembling the structure.

The second half 32a of the bit 30 is illustrated 30 as being provided with similar conduits 36a and 37a which perform similar functions for this bit half.

It will be observed that from the construction 40 of the bit halves thus described, the upper end of each of the bit halves forms a pair of semi-cylindrical portions, one of which constitutes one-half of the bit head 28 and the other of which forms one-half of the extending stem 35 so that 45 the assembled structure provides a completely cylindrical bit head 29 and an extending stem 35 formed thereon.

If desired, means to prevent relative movement 50 of the two halves 32 and 32a may be employed, such as a rectangular key 43, while suitable bolts 44 may be provided to secure the two halves of the bit 30 together.

The operation of the assembly just described is 55 as follows:

The reamers 18 may be assembled as herein described in the pockets 4, 5, and 6, the shafts 13 therefor being suitably screwed down and pinned in place by means of pins 17. The reamer carrier assembly may then be attached to the rock 60 bit assembly 30 by screwing the head 29 into the threaded portion 28 of the interior openings 27. It is assumed that the cone cutters employed on the bit 30 are in place and at this point the lubricant conduit 26 may be inserted through the interior opening 2 in the body member 1 and secured by means of a suitable coupling, not shown, to the extending stem 35 of the rock bit 30. The upper end of the body member 1 may be then secured to the drill string or to the power application and lowered into cutting position in the bore which is to be driven.

The flushing fluid may be passed through the drill string in the well-known manner to communicate with the interior passage 2 of the body 75

member 1, from whence the flushing fluid will pass through the openings 24, 25 and 26 which lie outside of the lubricant conduit 23. The flushing fluid will pass to the top of the head 29 of the bit 5 30 and thence pass through the pipe sections 36, 37, 36^a and 37^a to the strata which is to be bored by the cone cutters.

While the construction illustrated and described herein is particularly adapted to a fabricated 10 method of construction, as by forming the body member 1 of a cylindrical blank and milling the reamer pockets therein with the further steps of welding the reamer bearing blocks 7 and 8 in the milled opening and further welding the backing 15 plate or sealing plate 22 to the blocks 7 and 8, it will also be understood that the construction also is adapted to the casting process wherein the reamer pockets 4, 5 and 6 may be directly cast into the body member 1.

20 It will be apparent that many changes from the precise construction shown herein may be made and I therefore do not desire to be limited to any of the details shown herein, except as defined in the appended claims.

25 I claim:

1. In a rock bit and reamer assembly, a cylindrical body member having a central passage therethrough and having recessed therein a plurality of reamer pockets communicating with 30 said central passage, reamer bearing blocks secured in said pockets, interior plates secured to said blocks and said body member to seal the pockets from said central passage, a reamer rotatably mounted in each pocket, and a rock bit 35 threaded into one end of said body member, said bit having one or more lubricant passages communicating with a stem projecting into the central passage and also having one or more water passages communicating with the central passage 40 outside said stem, a lubricant pipe secured on said stem and of such size as to be tangent to the inner faces of the interior plates to form water passages between the pipe, the plates and the

portions of the cylindrical wall of the passage lying between the plates.

2. In a rock bit and reamer assembly, a cylindrical body member having a central passage therethrough and having recessed therein a plurality of reamer pockets communicating with 5 said central passage, reamer bearing blocks secured in said pockets and interior plates secured to said blocks and said body member to seal the pockets from said central passage, a reamer rotatably mounted in each pocket, a rock bit 10 threaded into one end of said body member, said bit having a pair of cone cutter bearings thereon, a lubricant passage extending through each cutter bearing and communicating with a stem 15 projecting into the central passage in the body member, said bit also having one or more water passages therethrough communicating with said central passage independent of said stem, and a lubricant pipe secured on said stem extending 20 upwardly into said central passage and contacting with said plates, said pipe being of such size as to be tangent to the interior plates to form water passages between the pipe and the portions 25 of the cylinder lying between the plates.

3. An article of manufacture comprising a reamer formed with a cylindrical body member having a circular cross sectional central bore extending longitudinally therethrough, a lubricant pipe passing through said bore, a plurality of 30 reamer pockets extending radially through the walls of said body member into communication with said central bore, reamer cutter bearing blocks secured at the longitudinal ends of each 35 of said pockets, a flat plate secured to the bearing blocks in each pocket to seal that pocket from communication with said central bore and to contact tangentially with the surface of a lubricating pipe passed through said central bore to divide the space between such lubricating pipe 40 and the walls of said body member into a plurality of fluid passages.

ARTHUR F. SPENGLER.
